UNITED STATES PATENT OFFICE.

ALBERT E. KEYSER, OF CHATTANOOGA, TENNESSEE.

REFRIGERATOR.

SPECIFICATION forming part of Letters Patent No. 668,563, dated February 19, 1901.

Application filed October 29, 1900. Serial No. 34,820. (No model.)

To all whom it may concern:

Be it known that I, ALBERT E. KEYSER, a citizen of the United States, residing at Chattanooga, in the county of Hamilton and State of Tennessee, have invented a new and useful Refrigerator, of which the following is a specification.

This invention relates to refrigerators; and the objects of the same are to provide a simple and effective construction; to obtain a very dry and cold refrigerator which can be used for households, hotels, grocers, butchers, fruit and wine dealers, and others; to obtain an extremely low temperature with a minimum amount of ice or other refrigerant, and thereby reduce the cost of maintaining this class of devices; to have a removable ice-chamber which is easily accessible for filling and arranged to have the water produced by the melted ice drawn therefrom without removing it and exteriorly of the refrigerator without opening the doors to the food or storage chamber, thereby preventing the escape of the cold air in the refrigerator and the inrushing of warm air into the latter and a consequent economy in the use of ice; to have the ice-chamber so situated as to increase the capacity of the storage-chamber for food and perishable articles and continue the extent of the ice-chamber to such a degree as to equally cool the storage-chamber throughout its entire area, and thus produce a quick chilling effect on the articles in the latter chamber; to provide means for carrying off any possible water of condensation to the exterior of the refrigerator without allowing it to drip onto any portion of the storage-chamber proper and including a device for excluding the entrance of warm air into said latter chamber, thereby always keeping the food or other articles dry and cold, and to overcome the numerous disadvantages incident to the use of the ordinary ice-chambers and air-ducts and the unsanitary wet condition of the parts of refrigerators now commonly employed.

The invention consists in the construction and arrangement of the several parts in general and in detail and subject to a wide range of modification in form, size, proportions, and minor features within the scope or principle of the invention.

In the drawings, Figure 1 is a perspective

view of a refrigerator embodying the features of the invention and showing the doors open. Fig. 2 is a longitudinal vertical section of the same, taken in advance of the ice-chambers. Fig. 3 is a horizontal section on the line 3 3, Fig. 2. Fig. 4 is a perspective view of one of the ice-chambers and a portion of the top of the refrigerator and the intimately-related parts shown disconnected therefrom and the ice-chamber also illustrated in a slightly-withdrawn condition. Fig. 5 is a detail perspective view of one of the racks or trays.

Similar numerals of reference are employed to indicate corresponding parts in the several views.

The numeral 1 designates a refrigerator frame or casing constructed of suitable material and of any preferred or desired shape, the accompanying drawings showing a household or simple form of refrigerator to illustrate the principle involved in the improvement and capable of introduction into any other form of like device. In general structure the refrigerator frame or casing will be in accord with the most approved features conducive to the exclusion of exterior heat and the maintenance of an interior low degree of temperature, and in the present instance it comprises an outer wood or analogous casing 2, an inner wall 3 of insulating-paper thereagainst, a dead-air space 4, a waterproof insulating-paper wall 5 against an inner wood or analogous casing 6, an insulating-paper lining 7 on the inside surface of said casing, and an interior sheet-metal lining 8 of a galvanized nature or zinc or nickeloid.

The present form of the improved refrigerator comprises two removable ice-chambers 9, located at the back and disposed vertically. These chambers are exposed in the storage-chamber 10, and preferably triangular in form to snugly fit in the rear corners of the said chamber 10, and the capacity of the latter chamber thus materially increased in view of dispensing with the ordinary form of ice-chamber at the upper portion. The ice-chambers 9 extend downwardly to within a short distance above the bottom of the storage-chamber, and the bottoms 11 incline downwardly and outwardly toward the rear corners of said latter chamber to cause the water produced by the melted ice to be di-

rected toward the apices of the said bottoms, and in the sides of said ice-chambers that rest against the sides of the storage-chamber are screw-taps 12, which are low enough to practically drain the water from the ice-chambers, and in the said taps the inner screw-threaded extremities of drain-cocks 13 are removably secured and have their outlets exteriorly located at opposite sides of the refrigerator. When the ice-chambers are removed, the drain-cocks are disconnected, and after replacement of the said chambers in the refrigerator the said cocks are again connected up, the parts being so proportioned that when the ice-chambers are fully inserted the taps 12 will coincide with the openings through the sides of the refrigerator for said cocks. The ice-chambers in the present instance are removable through suitable openings 14, formed in the top 15 of the refrigerator, a molding 16 being secured around the said openings to thereby provide ledges 17. At one side the said openings 14 are provided with closures 18 of suitable material and horizontally disposed below the level of the upper surface of the top 15 of the refrigerator to provide seats or supports for the removable reception of rectangular flanged suspending-collars 19 at the upper terminals of the ice-chambers, the said collars also preventing the latter chambers from turning and exteriorly indicating when they are in proper position without opening the refrigerator and exteriorly expose the storage-chamber. The said collars are dished, and thereby also serve to assist in filling the ice-chambers with ice or other refrigerating material, and the inlets to the latter chambers are closed by suitably-packed triangular lids or covers 20, and when the upper ends of said chambers are fully seated the collars 19 will be completely closed in by outer covers 21, resting on the ledges 17, and having portions extending downwardly into said collars, and thereby thoroughly protect said upper ends of the ice-chambers from the disadvantageous influence of the outer warm air.

In the event of a possible condensation on the surfaces of the ice-chambers within the storage-chamber and a descent thereover of the water of condensation provision is made to prevent the latter from dripping into any part of the said storage-chamber in the form of inverted triangular catch-basins 22, which are disposed at a suitable distance beneath the lower extremities of the ice-chambers, and having a top area greater than the cross-sectional extent of the latter chambers in order to insure a reception of all the water. The said catch-basins incline toward the rear corners of the storage-chamber at the bottom and have their apices connected to the vertical members of drain-pipes 23, having an outlet through the bottom of the refrigerator and provided with traps 24 to form water seals, and thereby prevent ingress of the exterior air, and thus preserve the cold temper-

ature of the storage-chamber without the least change, and yet effectively relieve the latter chamber of all moisture and facilitate keeping the air therein in a dry condition with obvious advantages. The storage-chamber by this means is also clear of any form of trough, gutter, or other sloppy incidental feature usually found in the ordinary refrigerators, and the food or other articles are chilled in a perfectly dry condition.

In the foregoing description the ice-chambers and catch-basins have been referred to as triangular in form and two in number; but it will be understood that the principle of the invention can be evolved equally as well from other contours, and in some instances only one ice-chamber and basin will be necessary. In gaining access to the storage-chamber two doors 25 are shown in the present instance, which will be suitably packed and may have glass panels therein. By the use of two doors articles in the upper part of the storage-chamber are made accessible without directly exposing those below, and vice versa; but in other constructions only one door may be used, and in either arrangement tightly-holding catches or locks will be employed to hold the doors closed.

Within the storage-chamber at different elevations ledge-brackets or analogous devices 25' are secured, on which racks or trays 26 are removably mounted, and in the present construction of the refrigerator they are of the form shown by Fig. 5 and have the rear corners removed to compensate for the projection of the ice-chambers, though other forms may be used. These racks or trays have a body 27, of wire, to permit a thorough and unobstructed circulation therethrough of the cold air and provided with an edge binding 28, of suitable sheet metal, to strengthen the same. The ice-chambers are also formed of suitable sheet metal, and a material advantage exists in not having the same attached by nails or screws, as the latter soon corrode and shrink away from their holding means, and thereby produce leaks. If the ice-chambers become injured, they can be easily removed and repaired at a small cost, or others can be substituted therefor in case they become so much worn that repair would be unprofitable. In general, the construction set forth is conducive to economy by reason of acquiring a maximum amount of coldness by a minimum consumption of ice, and, moreover, a freezing temperature can be obtained by application of salt to the ice in the ice-chambers. Furthermore, the construction of the ice-chambers and their placement, as set forth, whether in double or single form, renders it possible to easily obtain a maximum amount of storage-space for food and other articles, with a minimum space for storage of ice and a minimum space occupied by outside measurement of the refrigerator.

The construction of the refrigerator set forth makes a valuable wine-closet, as the bot-

bles can be laid on their sides and be kept very cold without the direct application of ice and without putting the bottles in troughs supplied with ice-meltings or allowing the ice-drippings to fall on them, and thus make the bottles cleanly and convenient in handling for dispensation of their contents.

Many other advantages and conveniences will become apparent by the use of the improved refrigerator, and the particular disposal of the removable ice-chambers to create extended cooling-surfaces is the essential factor of the invention. Furthermore, the benefits obviously arising from retaining the ice-water within the ice-chambers is also a potent advantage in the present construction. It is also proposed to use any kind of rack within the storage-chamber that is applicable for the purpose, and that form well known to me and having a wire body with a tubular edge will at times be preferred.

Having thus described the invention, what is claimed as new is—

1. A refrigerator having an unobstructed storage-chamber extending completely from the bottom to the top of the interior thereof, completely-closed removable ice-chambers normally located in the rear corner portions only of said storage-chamber and of angular shape to prevent turning or displacement thereof, the lower ends of the ice-chambers being above the inner bottom portion of the storage-chamber, and catch-basins in the rear bottom corner portions of the storage-chamber below the lower ends of said ice-chambers and of greater extent at their upper portions than the maximum horizontal extent of the latter chambers.

2. A refrigerator having an unobstructed storage-chamber extending from the bottom to the top of the interior thereof, completely-closed removable ice-chambers normally located in the rear corner portions of the said storage-chamber and suspended from the top of the refrigerator to have the lower ends above the bottom of the storage-chamber, inverted angular catch-basins below the lower ends of the ice-chamber, and trapped outlets secured to the downwardly-disposed apices of said basins.

3. A refrigerator having an unobstructed storage-chamber extending from the bottom to the top of the interior thereof, completely-closed removable ice-chambers normally located in the rear corner portions of said storage-chamber and having lower and downwardly and outwardly inclined ends with

tapped openings in the outer sides, said ends being above the bottom of the storage-chamber, exteriorly-projecting cocks having inner screw-threaded terminals to removably engage the tapped openings of the said lower ends of the ice-chambers, and means below the said lower ends of the latter chambers for catching the drippings therefrom and conveying them to the exterior of the refrigerator.

4. A refrigerator having an unobstructed storage-chamber, a top having angular openings therethrough at the rear communicating with top recesses, angular ice-chambers removable and insertible through said openings and having suspending-collars conforming in shape and adapted to snugly fit in said recesses to suspend the ice-chambers within the storage-chamber so that the lower ends of said chambers will be above the bottom of the latter chamber, removable covers to fit closely down in the upper ends of the ice-chambers, and outer covers to fit in and close over the collars and the removable covers for the ice-chambers.

5. A refrigerator having a storage-chamber, a top with an angular opening therein communicating with a rectangular recess, an ice-chamber of the same form as and freely removable through and insertible in said opening and having an upper rectangular dished collar to snugly fit said recess, a cover to fit flush down in the opening at the upper end of the ice-chamber, and an outer cover to fit in the collar and close over the said cover for the upper end of the ice-chamber.

6. A refrigerator having an unobstructed storage-chamber extending completely from the bottom to the top of the interior of the same, and triangular ice-chambers snugly and removably fitted in the rear corner portions of the said storage-chamber and having one side of each arranged obliquely from the end rearwardly toward the back of said storage-chamber to minimize the occupancy of space by the ice-chambers in the storage-chamber.

7. A refrigerator having an inverted angular catch-basin therein, and a trapped outlet secured to downwardly-disposed apex of said basin.

In testimony that I claim the foregoing as my own I have hereto affixed my signature in the presence of two witnesses.
